[57] CLAIM

The ornamental design for a carrier bag, substantially as shown and described.

DESCRIPTION

FIG. 1 is a perspective view of a carrier bag showing my new design;

FIG. 2 is a top plan view;

FIG. 3 is a front elevational view;

FIG. 4 is an elevational view looking from the right of FIG. 3;

FIG. 5 is a bottom plan view;

FIG. 6 is a fragmentary top plan view on an enlarged scale;

FIG. 7 is a fragmentary front elevational view of the handle;

FIG. 8 is a view looking from the left of FIG. 7; and

FIG. 9 is a rear elevational view thereof.

The curved lines shown in the handle which is viewed in FIGS. 2 and 6 designate cut edges of the material.
